UNITED STATES PATENT OFFICE.

GEORGE M. EATON, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRIC LOCOMOTIVE.

1,171,600.

Specification of Letters Patent. Patented Feb. 15, 1916.

Application filed June 23, 1913. Serial No. 776,210.

To all whom it may concern:

Be it known that I, GEORGE M. EATON, a citizen of the United States, and a resident of Wilkinsburg, in the county of Allegheny and State of Pennsylvania, have invented a new and useful Improvement in Electric Locomotives, of which the following is a specification.

My invention relates to electric locomotives or other railway vehicles, and it has special reference to the construction of the running gear.

One of the objects of my invention is to provide a structure of the above indicated character which shall be simple and durable in construction, and which shall be particularly adapted to lend strength and rigidity to the running gear and, more specifically, to the pedestal structure.

When locomotives are provided with side frames which are located outside of the driving wheels, it is customary to provide auxiliary pedestals which are secured to the side frames and which project inwardly to coöperate with the driving journal boxes. In cases where this type of construction is employed, the auxiliary pedestals are subjected to excessive lateral strains by reason of the fact that the driving force is transmitted through the pedestals at substantially their free ends.

It is the purpose of my invention to provide means, associated with the free ends of the auxiliary pedestals, for bracing them and maintaining them rigidly in position, as well as for strengthening the general structure of the running gear.

My invention may best be understood by reference to the accompanying drawing, in which—

Figure 1 is a view, in side elevation, of a portion of a locomotive running gear embodying my invention, certain parts being broken away for the sake of clearness. Fig. 2 is a plan view, partially in section, of the structure shown in Fig. 1, and Fig. 3 is a sectional view taken along the line III—III of Fig. 2.

Referring to the drawing, the running gear shown embodies a side frame 1 which is provided with a pair of auxiliary pedestals 2, that are independently secured thereto and project inwardly in a transverse direction to receive a driving journal box 3

which coöperates with an end 4 of a driving shaft or axle 5 in the usual manner. The axle 5 is provided with a driving wheel 6 which is disposed inside of the side frame 1.

The side frame 1 is of the plate frame type and has an opening 7 therein to accommodate the journal box 3 and the pedestals 2. Any other suitable frame construction may be employed. The journal box 3 forms no material part of my invention, except as it constitutes a necessary member in a useful combination of elements, and, hence, it may be constructed in any well known manner. The pedestals 2 are of like construction, and each comprises a longitudinal portion 8 which rests against the inner surface of the side frame 1 and is riveted or otherwise suitably secured thereto. Integrally associated with the portion 8 and projecting substantially at right angles thereto is a portion 9, the inner free end 10 of which constitutes a bearing surface for engagement with a pedestal shoe 11, which is interposed between said surface and the journal box 3. The portions 8 and 9 of the pedestal 2 are rigidly braced by a plurality of integral triangular webs 12. Substantially midway across the face of the upper web 12 is an integral flange 13 which projects upwardly and is disposed longitudinally and parallel to the side frame 1.

The pedestals 2 are disposed in pairs on the respective sides of the journal box 3, and the side frame 1 is trussed and braced laterally by means of cross ties 14, which are severally located on the opposite sides of the pair of pedestals 2. The cross ties 14 are preferably of plate construction and are riveted solidly to the side frame 1.

In order to strengthen and reinforce the pedestals 2 against lateral strains, I provide a longitudinal bracing member 15 which is substantially channel shape in section and which rests upon the upper surfaces of the top webs 12 and engages and is secured to the longitudinal flanges 13 of the several pedestals 2. Moreover, the respective ends of the member 15 are attached rigidly to the cross ties 14 and also to the inside frame 1 in a suitable manner.

I do not wish to be restricted to the particular structural details and arrangement and location of parts hereinbefore shown and described, as I contemplate modifica-

tions which may vary widely from what is set forth.

I claim as my invention:

1. In a vehicle, the combination with a side frame and auxiliary pedestals secured to said frame, and having longitudinal upwardly projecting members near the free ends thereof, of bracing means secured to said upwardly projecting members of said pedestals.

2. In a vehicle, the combination with a side frame and auxiliary pedestals secured to said frame and projecting transversely therefrom, of a bracing member secured to said frame and engaging the free ends of said pedestals.

3. In a vehicle, the combination with a side frame and auxiliary pedestals secured to said frame and projecting transversely therefrom, of a longitudinal member attached to said frame on each side of said pedestals and rigidly associated with free ends thereof.

4. In a vehicle, the combination with a side frame and auxiliary pedestals secured to said frame and projecting transversely therefrom, of a longitudinal bracing member associated with said frame and engaging the upper surfaces of the free ends of said pedestals and fastened thereto.

5. In a vehicle, the combination with a side frame and transversely projecting pedestals independently attached thereto, of means secured directly to said side frame and engaging said pedestals for rigidly bracing said pedestals against lateral strains.

6. In a vehicle, the combination with a side frame, auxiliary pedestals, and means for transversely bracing said frame, of means associated with said bracing means

for rigidly securing said pedestals in position.

7. In a vehicle, the combination with a side frame, auxiliary pedestals, and means for transversely bracing said frame, of single means associated with said bracing means and the free ends of said pedestals, for bracing said pedestals against lateral strains.

8. In a vehicle, the combination with a side frame, auxiliary pedestals secured thereto, and cross ties transversely bracing said side frame, of a longitudinal member attached to said pedestals and cross ties for rigidly securing said pedestals in position.

9. In a locomotive, the combination with a side frame, a pair of auxiliary pedestals secured independently thereto and projecting inwardly therefrom, and cross ties disposed on each side of said pair of pedestals, of a longitudinal bracing member fastened to said cross ties and rigidly associated with the free ends of said pair of pedestals.

10. In a vehicle, the combination with a side frame and auxiliary pedestals secured thereto and projecting transversely therefrom, of means for transversely bracing said frame and other means associated with said bracing means and with said frame for bracing said pedestals against lateral strains.

In testimony whereof, I have hereunto subscribed my name this 27th day of June, 1913.

GEORGE M. EATON.
